POLYCHROME TELEVISION SCREEN AND
PROCESS OF MANUFACTURE

Roger Guy, Clamart, France, assignor to Compagnie de
Saint-Gobain, Neuilly-sur-Seine, France
Filed May 10, 1961, Ser. No. 109,053
Claims priority, application France Apr. 30, 1959
20 Claims. (Cl. 313—92)

This invention relates to polychrome striped screens for use in color television.

It is known that it is possible to reconstitute the color scale by combination of at least three appropriate primary colors. This principle is the basis of the largest part of color television systems, which utilize the principle of splitting up an image into three monochromatic images each of which is in one of three primary, coordinate colors; the three images are transmitted electronically to the receiving screen. Generally these screens are of the polychrome type and are viewed with direct vision. Some of the screens are made by the dot stippling of pin-point elementary surfaces onto a transparent support and others are made by the application to the support of parallel stripes. Dots and stripes are generally made of fluorescent substances which emit, under the impact of an electronic beam, a light which is colored according to that one color of the primary colors in the screen which is found in the particular dot or stripe. The parallel stripes are preferable to the stippled surfaces, both for their luminous efficiency and for easier manufacture.

It is also possible to use screens constituted by a film of pigments with white homogeneous luminescence, in front of which is placed a conveniently colored optical filter. In the tubes for color television used until present time, a striped colored fluorescent screen is laid down on the bottom of the tube and at a very short distance of the screen a grid is set, whose wires are in a rigorously determined position in relation to the stripes of the screen. The practical application of these grids and their placing in the receiver tubes are delicate operations as the wires have in particular a tendency to distend under the influence of temperature changes during the mounting of the tube and during its use.

These drawbacks can be partially avoided by binding the wires of the grid to the screen, but the correct positioning of the wires remains a difficult problem.

It is an object of this invention to prepare a superior television tube which is efficient and presents less of a problem of manufacture. Another object is to do away with the control filaments which have been used between the colored triads in some construction. Another object is to supply a superior tube useful without alteration in systems such as the de France system of French Patents 664,080 and 1,087,363. Another object is to prepare tubes for use with color which are equally useful in black and white transmission. Other objects will appear as the description proceeds.

The objects are accomplished, generally speaking, by a television tube having a transparent polychrome screen comprising a transparent objective plate, a series of opaque, parallel bands applied to the plate at equal intervals, a continuous, conductive, transparent layer coating the plate and said opaque bands, colored plurads composed of parallel stripes in compatible colors carried by the said conductive layer, arranged in alignment with the spaces between the opaque bands and exposing strips of the conductive layer above the opaque bands, and a white, luminescent layer covering the plurad groups, and by a method of making such tubes by the application of stripes of enamels, a layer of transparent metal or metal oxides, stripes of colored enamel, and a layer of white luminescence.

2

The tube face, target, or objective is preferably glass but may be composed of any transparent material having adequate strength, for instance quartz.

The opaque enamels applied to the tube face are electrically non-conductive, are applied in thin stripes spaced apart the width of a triad, or plurad as the case may be, and are baked on.

Over the opaque enamel stripes and the whole useful face of the tube is applied a layer of transparent conductive material of which metal oxides or metal are preferred. This can be applied by precipitation from a solution of a metal salt and a reducing agent, preferably while the tube face is still hot from the baking of the enamel. This conductive layer is slightly elevated over the opaque strips, forming channels which receive the triads. After the precipitation of the conductive layer the tube is eventually dried at elevated temperature to remove the precipitating solution.

The colored triads are applied in parallel stripes of enamels in alignment with the spaces between the opaque strips. These triads are composed of contiguous, non-conductive stripes of enamel each stripe of which is colored by a different colored pigment, the colors being compatible, and primary. The continuous conductive coat is exposed between the triads over the opaque stripes and the exposed part serves the purposes of a conductive filament.

The stripes may all be of the same size, for instance 0.4 mm. in width. They may be applied by any known method, such as by the silk screen and offset processes, which are well able to apply such fine lines in parallelism and contiguously.

Over the colored triads is applied a layer of white luminescence of any known type, all of which are useful, both those previously used with color and those used with black and white projection.

The above and further objects and novel features of the present invention will more fully appear from the following detailed description when the same is read in connection with the accompanying drawings. It is to be expressly understood, however, that the drawings are for the purpose of illustration only and are not intended as a definition of the limits of the invention, reference for this latter purpose being had primarily to the appended claims.

In the drawings, wherein like reference characters refer to like parts throughout the several views,

FIG. 1 is a perspective view, partly cut away, showing a section, A, taken out of the face of a television tube;

FIG. 2 is an enlargement of section A, diagrammatically presented; and

FIG. 3 is a perpendicular section, on enlarged scale, through the face of a television tube such as that of FIG. 1.

Referring to the numerals of the drawing, a television tube 10, having a glass face 11, is provided at spaced intervals, on its inner face, with opaque stripes 12 which extend in straight, parallel lines across the whole target area. These stripes may be of the same width as each of the colored stripes of the triads, for instance 0.4 mm. and they are composed of low melting enamels containing opaques pigments, of which the following is a typical formula:

	Percent		Percent
SiO ₂	30	ZrO ₂	0.5
Al ₂ O ₃	2	Li ₂ O	1.5
Na ₂ O + K ₂ O	1.5	Fe ₃ O ₄ *	4.4
B ₂ O ₃	2.5	Cr ₂ O ₃ *	4.4
BaO	2	MnO ₂ *	1
PbO	50	CoO*	0.2

70 *Opaquing pigments.

The opaque stripes of 0.4 mm. width are applied to the

face of the tube in parallel and equally spaced lines separated by spaces of 1.2 mm. in width across the inner face of a television screen. The stripes are applied by known methods as offset, silk screen, etc.

After the opaque enamel stripes have been applied to the tube face, the tube face is baked at a temperature on the order of about 550° C. which permanently sets the stripes.

The hot tube face then receives a conductive layer of transparent metal oxide or metal for example a mixture of stannous oxides or stannous and antimonium oxides. Useful examples of the conductive layer are tin, antimony, indium, cadmium and their oxides. The tube face must be baked before spraying to about 400-450° C. Typical conductive mixtures are:

(1)

	Parts by wt.
10% SnCl_4 in ethyl alcohol (industrial)	100
Formaldehyde	10
HCl (industrial)	15

(2)

10% SnCl_4 in ethyl alcohol	100
Formaldehyde	10
50% SbCl_5 in ethyl alcohol	1.2
HCl	15

The solution is preferably applied while the tube face is still hot from the baking of the opaque enamel stripes and cooled to said temperature of about 400-450° C. A thin metallic film 13 forms over and covers the inner face of the plate 11, including the opaque stripes 12. This layer is electrically conductive and the portions 13', elevated above the stripes 12, perform the function that was previously performed by the wires of the conductive grid. In the other embodiments the wires had to be joined together, whereas according to our invention the unitary nature of the metallic layer obviates that difficulty and provides a better structure.

The layer 13 is transparent, but the opaque stripes 12, beneath the conductive stripes 13', stop the rays that might pass through those lines, so that only the rays from the stripes are seen.

The triads are three enamel stripes, for instance 14 for red, 15 for green, and 16 for blue, applied between the elevated stripes 13'. Stripes 13', 14, 15, and 16 are contiguous. Stripes 13' is part of the conductive layer 13, but stripes 14, 15, 16 are non-conductive, colored enamels. The enamels are vitrified, as are also the opaque enamels, at a temperature of about 500-550° C. after they have been applied. The triad enamels may be composed of low melting point vitreous enamels having for example the following composition:

	Percent	Percent	
SiO_2	3.4	Al_2O_3	2.2
Na_2O	0.4	PbO	53
B_2O_3	25	BaO	16

The coloration may be obtained by means of $\text{Se}+\text{SCd}$ (for red), CoO (for blue), Cr_2O_3 with or without copper oxide or cobalt oxide for green color.

After the enamels are applied manually or by silk screen or other satisfactory methods the plate is again baked at the fusing temperature of the enamels, about 500-550° C. and cooled. To this plate is added, over the triads, a white luminescent layer 17 of ordinary constitution containing ZnS and/or CdS and activators. These compositions are known, are on the market, and the different activators as well as the compositions are usually described in the sales literature of the manufacturers.

The luminescent layer is obtained by sedimentation of luminescent powders. Said layer is fixed by spraying of a solution of sodium silicate followed by heating to about 400° C. during 20 minutes.

A particular advantage of this invention lies in the substitution of the novel continuous conductive layer for the wire grid or prior constructions. Another advantage is the enamelled constitution of the tube face and the permanence resulting therefrom. Another advantage arises from the fact that any enamels softening below the softening temperature of the glass of the tube face can be used, which gives a very wide selection of compositions.

The invention may be summarized as follows:

Existing tubes have fluorescent, colored, lined screens in which the colored lines are applied to the face plate of the tube, adjacent to which is a grill having its wires in position rigorously fixed by the lines of the screen. Those wire grills are a source of difficulty by reason of their tendency to warp. They can be made better by fixing them in place against the screen but they remain a source of difficulty as it is hard to attach them accurately.

The present invention is of the type having a white luminescent layer over a tricolored lined filter, and is characterized by a grill constituted by a continuous, transparent, conductive layer applied to the glass of the tube face, upon which are disposed at equal intervals, the transparent and non-conductive colored triads, exposing between adjacent triads strips of the conductive layer which act as elements of the grill and which are adapted to be in alignment with the control rays of the tube. An opaque stripe is mounted on the tube plate immediately under each exposed conductive stripe in order to mask the white light, unfiltered, which enters the exposed conductive stripes.

The transparent conductive layer may advantageously consist of a very thin metallic or metal oxide film, which are placed, after the plate of the tube has received the opaque stripes. These stripes may be obtained by the process cited there above or by all known processes.

The opaque bands and colored triads are composed of enamels containing appropriate pigments to supply the opacity or the color as the case may be. In order to assure the electrical isolation of the zones covered by the triads, the colored stripes of each triad are made contiguous.

A major advantage of the invention is the elimination of the metallic grid and the elimination of the labor and difficulty of making electrical connections between all the elements of the metallic grid.

In the practical application of the invention, one applies to the glass which is to form the target of the tube, its face plate, with precise spacing, black enamel stripes by offset, or by silk screen techniques, which have this capacity and do not need description. The black enamel stripes are baked at temperatures which fix them to the glass, then, without letting the glass cool, one sprays a mixture of anhydrous stannic chloride, antimony chloride, and formaldehyde in ethyl alcohol onto the plate, the reduction proceeds and deposits a metallic or metal oxide film, and eventually dry the coat, which is conductive and transparent. The triads are then applied in accordance with prior practice, taking care to leave between each pair of triads a spaced aligned with the stripes of black enamel.

In considering the drawings of this case it should be realized that they are diagrammatic and are not intended to be an accurate representation of form, proportion, or size.

This case is a continuation-in-part of my application Serial No. 24,655 filed April 26, 1960.

As many apparently widely different embodiments of the present invention may be made without departing from the spirit and scope thereof, it is to be understood that the invention is not limited to the specific embodiments.

What is claimed is:

1. A cathode ray screen having a transparent polychrome screen comprising a transparent objective plate, a series of opaque, parallel bands applied to the plate at

equal intervals, a continuous, conductive, transparent layer coating the plate and said bands, colored plurads composed of parallel stripes in compatible colors carried by said conductive layer, arranged in alignment with the spaces between the opaque bands and exposing stripes of the conductive layer above the opaque bands, and a white, luminescent layer covering the plurad groups.

2. A cathode ray screen having a transparent poly-chrome screen comprising a transparent glass objective plate, a series of opaque, parallel, non-conductive enamel bands applied to the plate at equal intervals, a continuous, conductive, transparent layer coating the plate and said bands, colored triads comprising three coordinate primary colors composed of parallel, non-conductive enamel stripes carried by said conductive layer, arranged in alignment with the spaces between the opaque bands and exposing stripes of the conductive layer above the opaque bands, and a white luminescent layer covering the triads and the exposed parts of the conductive layer.

3. A cathode ray screen according to claim 2 in which the conductive layer is metal.

4. A cathode ray screen according to claim 2 in which the conductive layer is metal oxide.

5. A cathode ray screen according to claim 2 in which the triads are composed of non-conductive enamel stripes in three primary colors.

6. A cathode ray screen according to claim 2 in which the conductive coat comprises tin.

7. A cathode ray screen according to claim 2 in which the conductive coat comprises tin and antimony.

8. A cathode ray screen according to claim 2 in which the conductive coat comprises tin oxide.

9. A cathode ray screen according to claim 2 in which the conductive coat comprises tin and antimony oxide.

10. A cathode ray screen according to claim 2 in which the conductive coat comprises indium.

11. A cathode ray screen according to claim 2 in which the conductive coat comprises indium oxide.

12. A cathode ray screen according to claim 2 in which the conductive coat comprises cadmium.

13. A cathode ray screen according to claim 2 in which the conductive coat comprises cadmium oxide.

14. A method of making a television tube which comprises applying to the glass face of a tube evenly spaced stripes of opaque, non-conductive enamel, baking the enamel, coating the glass face of the tube evenly with a solution of a reducible metal salt and a reducing compound while the glass is at moderately elevated temperature, thereby coating the glass and spaced stripes with a transparent, conductive coat, applying tricolor triads of non-conductive enamel in alignment with the spaces between the opaque stripes, leaving the conductive coat exposed over the opaque stripes, and baking the enamel, and applying to the face of the tube, over the triads, a luminescent white coating.

15. A manufacturing process of a color television screen, consisting in laying down on the bottom of the tube evenly spaced stripes of black opaque enamel, baking said enamel, covering the whole area of the said bottom surface with a continuous conducting transparent layer, and laying down isolating trichromous juxtaposed transparent stripes, covering the whole said bottom area with a uniform layer of luminescent white pigments.

16. A manufacturing process of a color television screen, consisting in laying down on the bottom of the tube evenly spaced opaque stripes, covering the whole area of the said bottom surface with a continuous con-

ducting transparent layer, laying down isolating trichromous transparent stripes over the areas between the said opaque stripes, and covering the whole said bottom area with a uniform layer of luminescent white pigments.

5. 17. A manufacturing process of a color television screen, consisting in laying down on the bottom of the tube evenly spaced stripes of black opaque enamel, baking said enamel, spraying the whole area of said bottom surface with a solution of reducible metallic salt and reducing said compound while the glass of the said bottom surface has not yet cooled, obtaining through the reduction of the said metallic salt a uniform transparent conducting film covering the whole bottom area of the tube, laying down transparent insulating juxtaposed stripes of enamels of three different colors, so as to cover the areas between the said black stripes, and covering the whole said bottom area with a uniform layer of luminescent white pigments.

18. A color television receiver tube comprising a plurality of opaque parallel stripes disposed at predetermined intervals on the inner surface of the target face of said tube, a transparent conductive layer having a lower surface disposed over said opaque stripes and said intervals, a plurality of parallel predetermined colored stripes, said predetermined colored stripes being disposed on the upper surface of said conductive layer between and parallel to said opaque stripes in composite coloring groups, said conductive layer having portions disposed between said groups, and a luminescent layer having a lower surface adapted to cover said colored stripes and said portions at the upper surface of said conductive layer disposed between said groups.

19. A screen adapted to intercept an electron beam to provide a composite color image thereon, said screen comprising a transparent layer, a plurality of opaque parallel stripes disposed at predetermined intervals on the surface of said transparent layer, a transparent conductive layer having a lower surface disposed over said opaque stripes and said intervals therebetween, a plurality of parallel predetermined colored stripes, said predetermined colored stripes being disposed on the upper surface of said conductive layer between and parallel to said opaque stripes in composite coloring groups, said conductive layer having portions disposed between said groups, and a luminescent layer having a lower surface adapted to cover said colored stripes and said portions at the upper surface of said conductive layer disposed between said groups.

20. A method of making a color television receiver tube which comprises disposing on the inner surface of the target face of said tube a plurality of parallel opaque stripes in a predetermined fixed relationship covering said opaque stripes and said intervals therebetween with the lower surface of a transparent conductive layer, disposing on the upper surface of said conductive layer parallel predetermined colored stripes, said colored stripes being arranged in composite coloring groups and parallel to and between said opaque stripes, portions of said conductive layer being disposed between said groups and disposing a luminescent layer over said groups and said portions of said conductive layer.
